COMBINED HEDDLE AND LINGO AND METHOD OF MAKING THE SAME

Filed June 24, 1927

Inventor:
John Jacob Kaufmann
By Jas. C. Nobusmith
Attorney.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

COMBINED HEDDLE AND LINGO AND METHOD OF MAKING THE SAME

Application filed June 24, 1927. Serial No. 291,064.

My invention relates to combined heddles and lingo and the method of making the same, and it relates more particularly to the manner of connecting the lingo to the heddle whereby there is produced a composite article particularly adaptable for use in Jacquard looms and the like.

Heretofore, in the use of Jacquard loom harness, difficulties have been encountered at the point of attachment of the lingo to the heddle. By reason of the relative movement between the lingo and the eye usually provided at the lower end of the heddle, wear occurs at this point, and in course of time either the eye of the heddle or the corresponding portion of the lingo will be worn through, and the lingo thereby become detached. In other instances, the lingo becomes unhooked from the heddles during the manipulation of the same, and in other instances the free actuation of the heddles is interfered with by reason of enlargements at the point of attachment of the lingo to the heddle.

The object, therefore, of the present invention is to provide a combined heddle and lingo in which possibility of the lingo becoming detached from the heddle, either by wear or by becoming unhooked during the manipulation of the harness, will be eliminated. A further object of the invention is to provide such a device in which projections at the point of attachment of the lingo to the heddle will be reduced to a minimum. A further object of the invention is to provide an improved process of making a combined heddle and lingo whereby the same will be relatively inexpensive and easy to assemble.

With the foregoing objects in view, my invention contemplates the provision of a jacquard heddle made of thin, flat metal or wire, at the lower end of which a lingo is permanently attached in a simple, efficient and inexpensive manner.

The nature and characteristic features of my invention will be more readily understood from the following description, taken in connection with the accompanying drawings forming part hereof, in which:

Figure 1 is a front elevation of a combined

heddle and lingo embodying the main features of my present invention, and made according to the method thereof;

Fig. 2 is a side elevation thereof;

Fig. 3 is a perspective view of the end portions of the heddle and lingo before being attached to each other;

Fig. 4 is a similar view with the parts engaging each other at an intermediate stage of the method; and

Fig. 5 is a similar view with said parts at the finished or completed stage of the method.

Referring to the drawings, in the particular embodiment of my invention therein shown, 6 is a jacquard heddle, preferably made of thin, flat metal or wire, having an eye 7 at the upper end for the attachment of the control cord of the jacquard mechanism; a warp eye 8 intermediate the ends thereof; and an eye 9 at the lower end thereof for the attachment of the lingo 10.

In the fabrication of the device, the end of the lingo 10 is first flattened as at 11, and in the flattened portion 11 there is provided a slot 12. There is also provided a slit 13 extending from the middle portion of the slot 12 through one of the side walls of the flattened portion 11. The lower end of the heddle 6, beyond the eye portion 9, is provided with an extension 14 of such length as to fill out substantially the length of the slot 12 in the flattened portion of the lingo 10. The slit 13 in one of the side walls of the flattened portion 11 of the lingo 10 is of such size as to permit one of the side shanks of the eye portion 9 of the heddle to be inserted through said slit 13.

The parts being initially shaped as aforesaid, the eye portion 9 of the heddle 6 is now brought into engagement with the flattened portion 11 of the lingo 10, by inserting one of the side shanks of the eye portion 9 of the heddle through the slit 13, the heddle being disposed at right angles to the lingo while being so inserted, after which the heddle is brought into alignment with the lingo 10, the parts then being in the position shown in Fig. 4 of the drawings.

The flattened portion 11 of the lingo is now subjected to a pressing or swaging operation

to cause the same to be shaped as shown in Figs. 1, 2 and 5 of the drawings, whereby the sidewise extensions of the flattened portion 11 are reduced to the initial dimensions of the cross section of the lingo, and at the same time the slot 12 in the flattened portion will be reduced, thereby to grip firmly the end portion 14 of the heddle 16 and hold the same against movement therein. At the same time, the slit 13 in one of the side walls of the flattened portion 11 of the lingo 10 will be closed as shown in Figs. 2 and 5 of the drawings.

In this manner, there will be produced a combined heddle and lingo in which relative movement between the lingo and the heddle will be eliminated, thus obviating wear at this point, as well as effectively preventing the accidental disconnection of the lingo from the heddle. It will also be noted that the sidewise projections in the lingo, usually found at the point of attachment to the heddle, will be eliminated, thus permitting greater ease of movement of the heddle and the lingo in the operation of the loom.

Having thus described the nature and characteristic features of my invention, what I claim as new and desire to secure by Letters Patent, is:

1. A heddle having an eye near the lower end thereof, and a lingo comprising a rod having a slot at its upper end within which the lower end of the heddle is fixedly positioned, the slotted portion of the lingo having rigid side walls closely engaging and gripping the lower portion of the heddle.

2. A heddle made of thin flat metal or wire having an eye near the lower end thereof, and a lingo comprising a rod having a slot at its upper end within which the lower end of the heddle is fixedly positioned, and the slotted portion of the lingo having rigid side walls closely engaging and gripping the lower portion of the heddle.

3. A heddle made of thin flat metal or wire having an eye near the lower end thereof and a portion projecting below said eye, and a lingo comprising a rod having a slot at its upper end within which the lower end of the heddle is fixedly positioned, and the slotted portion of the lingo having rigid side walls closely engaging and gripping the portion of the heddle below the eye.

4. A heddle made of thin flat metal or wire having an eye near the lower end thereof and a portion projecting below said eye, and a lingo comprising a rod having a flat portion at its upper end, said flat portion having a slot within which the lower end of the heddle is fixedly positioned, and the side walls of the slotted portion of the lingo engaging and gripping the portion of the heddle below the eye.

5. A heddle made of thin flat metal or wire having an eye near the lower end thereof and a portion projecting below said eye, and

a lingo comprising a rod having a flat portion at its upper end, said flat portion having a slot within which the lower end of the heddle is fixedly positioned, the side walls of the slotted portion of the lingo engaging and gripping the portion of the heddle below the eye, and one of the side walls of the flat portion having a slit through which one of the side shanks of the eye portion is initially inserted.

6. A heddle made of thin flat metal or wire having an eye near the lower end thereof and a portion projecting below said eye, and a lingo comprising a rod having a flat portion at its upper end, said flat portion having a slot within which the lower end of the heddle is fixedly positioned, the side walls of the slotted portion of the lingo engaging and gripping the portion of the heddle below the eye, one of the side walls of the flat portion having a slit through which one of the side shanks of the eye portion is initially inserted, and said slit being closed.

7. The method of attaching a lingo to a heddle which consists in forming an eye at the lower end of the heddle; forming a slot in the upper end of the lingo; engaging the eye portion of the heddle in the slotted portion of the lingo; and then compressing the sides of the slotted portion of the lingo to cause the end of the heddle to be firmly gripped in the slot of the lingo.

8. The method of attaching a lingo to a heddle which consists in forming an eye at the lower end of the heddle; flattening the upper end of the lingo; forming a slot in said flattened portion; engaging the eye portion of the heddle in the slotted portion of the lingo; and then compressing the sides of the slotted portion of the lingo to cause the end of the heddle to be firmly gripped in the slot of the lingo.

9. The method of attaching a lingo to a heddle which consists in forming an eye at the lower end of the heddle; flattening the upper end of the lingo; forming a slot in said flattened portion; engaging the eye portion of the heddle in the slotted portion of the lingo; and then compressing the sides of the slotted portion of the lingo to cause the end of the heddle to be firmly gripped in the slot of the lingo, at the same time reducing the width of the flattened portion of the lingo to the diameter of the body portion thereof.

10. The method of attaching a lingo to a heddle which consists in forming an eye at the lower end of the heddle; forming a slot in the upper end of the lingo, and a slit in one of the side walls thereof extending from the middle portion of the slot to the exterior; engaging the eye portion of the heddle by the upper portion of the lingo by inserting one of the side shanks of the eye portion of the heddle through the slit in the side wall of the slotted portion of the lingo; and then com-

pressing the sides of the slotted portion of the lingo to cause the end of the heddle to be firmly gripped in the slot of the lingo.

11. The method of attaching a lingo to a heddle which consists in forming an eye at the lower end of the heddle; flattening the upper end of the lingo; forming a slot in said flattened portion, and a slit in one of the side walls thereof extending from the slot to the exterior; engaging the eye portion of the heddle by the upper portion of the lingo by inserting one of the side shanks of the eye portion of the heddle through the slit in the side wall of the slotted portion of the lingo; and then compressing the sides of the slotted portion of the lingo to cause the end of the heddle to be firmly gripped in the slot of the lingo.

12. The method of attaching a lingo to a heddle which consists in forming an eye at the lower end of the heddle; flattening the upper end of the lingo; forming a slot in said flattened portion, and a slit in one of the side walls thereof extending from the slot to the exterior; engaging the eye portion of the heddle by the upper portion of the lingo by inserting one of the side shanks of the eye portion of the heddle through the slit in the side wall of the slotted portion of the lingo; and then compressing the sides of the slotted portion of the lingo to cause the end of the heddle to be firmly gripped in the slot of the lingo, at the same time reducing the width of the flattened portion of the lingo to the diameter of the body portion thereof.

13. The method of attaching a lingo to a heddle which consists in forming an eye at the lower end of the heddle; flattening the upper end of the lingo; forming a slot in said flattened portion, and a slit in one of the side walls thereof extending from the middle portion of the slot to the exterior; engaging the eye portion of the heddle by the upper portion of the lingo by inserting one of the side shanks of the eye portion of the heddle through the slit in the side wall of the slotted portion of the lingo; and then compressing the sides of the slotted portion of the lingo to cause the end of the heddle to be firmly gripped in the slot of the lingo, at the same time reducing the width of the flattened portion of the lingo to the diameter of the body portion thereof.

14. The method of attaching a lingo to a heddle which consists in forming an eye at the lower end of the heddle; flattening the upper end of the lingo; forming a slot in said flattened portion, and a slit in one of the side walls thereof extending from the middle portion of the slot to the exterior; engaging the eye portion of the heddle by the upper portion of the lingo by inserting one of the side shanks of the eye portion of the heddle through the slit in the side wall of the slotted portion of the lingo; and then compressing

the sides of the slotted portion of the lingo to cause the end of the heddle to be firmly gripped in the slot of the lingo, at the same time reducing the width of the flattened portion of the lingo to the diameter of the body portion thereof, and closing the slit in the side wall of the slotted portion of the lingo.

In testimony whereof, I have hereunto signed my name.
